(**) Term: **14 Years**

(57) CLAIM

(21) Appl. No.: **29/130,882**

The ornamental design for a truck frame crossmember, as
shown and described.

(22) Filed: **Oct. 10, 2000**

DESCRIPTION

(62) Division of application No. 29/114,465, filed on Nov. 29,
1999, now Pat. No. Des. 436,558.

FIG. 1 is a top perspective view of a truck frame crossmem-

(51) LOC (7) Cl. **12-08**

FIG. 2 is a bottom perspective view of the design;

(52) U.S. Cl. **D12/93**

FIG. 3 is a top plan view of the design;

(58) Field of Search **D12/93, 96, 97,**
D12/98, 99, 196; 296/180.1, 180.2, 181,
183; 280/788, 711-713, 498; 105/118.2

FIG. 4 is a bottom plan view of the design;

(56) References Cited

FIG. 5 is a side view of the design, as viewed from either

side; and,

FIG. 6 is an end view of the design, as viewed from either

end.
